UNITED STATES PATENT OFFICE.

LEE WARD, OF YANCEY, TEXAS.

DESIGN FOR AN ANTIRATTLER FOR WAGON-BODIES.

SPECIFICATION forming part of Design No. 34,830, dated July 23, 1901.

Application filed June 18, 1901. Serial No. 65,072. Term of patent 7 years.

To all whom it may concern:

Be it known that I, LEE WARD, a citizen of the United States, residing at Yancey, in the county of Medina and State of Texas, have invented and produced a new and original Design for Antirattlers for Wagon-Bodies; and I do hereby declare the following to be a full, clear, and exact description of the same, reference being had to the accompanying drawings, forming a part thereof.

My invention relates to antirattlers designed for wagon-bodies; and it consists in the new and original design illustrated in the drawings.

15 In the accompanying drawings, forming a part of this specification, Figure 1 is a side elevation of the antirattler, and Fig. 2 is a front elevation looking in the direction of the arrow shown in Fig. 1.

20 The essential feature of my design consists of a body portion formed of a coiled spring, its upper end terminating in a hook-shaped arm adapted to project and fit over or grasp the top portion of the sides of a wagon-body, 25 while the lower end of said body portion terminates in a perforated lug facing sidewise or at right angles to the hook-shaped arm and having its lower end bent to form a purchase or handle.

Referring more particularly to the drawings, A denotes the body portion of the antirattler, which consists of a coiled spring. 30

B denotes the hook-shaped arm projecting above the body portion and facing forward, as shown in Fig. 1. 35

C denotes a lug projecting below the spring and facing sidewise, as shown in Fig. 2, provided with perforations c c c, adapted to receive a bolt running sidewise through a standard of the wagon-body above the wagon-bed. 40 c' denotes the bent end of said lug, which serves as a purchase for bearing down on the spring when the antirattler is placed in position.

Having shown and described my invention, 45 what I claim as new, and desire to secure by Letters Patent, is—

The design for an antirattler for wagon-bodies substantially as shown and described.

In testimony whereof I affix my signature 50 in presence of two witnesses.

LEE WARD.
